Patented Oct. 16, 1973

228,649

LAWN TREATING TRAILER

Robert Picardat, 7712 Ridgecrest Drive,
Alexandria, Va. 22380

Filed May 6, 1971, Ser. No. 141,089

Term of patent 14 years

Int. Cl. D15—03

U.S. Cl. D35—2 R

FIG. 1.

FIG. 2.

FIG. 3.

FIG. 4.

FIG. 5.

FIG. 6.

FIG. 7.

FIG. 8.

FIG. 1 is a top plan view of the lawn treating trailer;
 FIG. 2 is a side elevation of the trailer;

FIG. 3 is a rear elevation of the trailer;

FIG. 4 is a bottom plan view of the trailer;

FIG. 5 is a side elevation of the trailer, looking at the side opposite FIG. 2;

FIG. 6 is a front elevation of the trailer;

FIG. 7 is a perspective view of the trailer as seen from the top and front thereof; and

FIG. 8 is a perspective view of the trailer as seen from the bottom and rear thereof.

I claim:

The ornamental design for a lawn treating trailer, as shown.
